UNITED STATES PATENT OFFICE.

LOUIS STEINBERGER, OF BROOKLYN, NEW YORK.

LOCKING-CLIP.

1,139,141.

Specification of Letters Patent. Patented May 11, 1915.

Application filed October 18, 1910 Serial No. 587,718.

To all whom it may concern:

Be it known that I, LOUIS STEINBERGER, a citizen of the United States, and a resident of the city of New York, borough of Brooklyn, in the county of Kings and State of New York, have invented a new and Improved Locking-Clip, of which the following is a full, clear, and exact description.

My invention relates to locking clips, such as are of particular service in supporting electric conductors, and more particularly for supporting overhead trolley wires.

Among the several objects of my invention are the following: I. To enable a clip, or analogous support for a conductor, to be readily secured to and detached from the hanger without releasing the hanger from its suspension mechanism. II. To adapt the same clip to fit hangers, or analogous supporting members, of different sizes. III. To avoid the necessity for turning the clip bodily upon an axis in mounting the clip upon the hanger or removing the same therefrom. IV. To facilitate the removal and replacement of various parts. V. To enable the clip to be fixedly secured at different predetermined angles relatively to the hanger. VI. To allow the clip freedom of rotation relatively to the hanger in instances where such freedom is desirable.

Reference is to be had to the accompanying drawings forming a part of this specification, in which similar characters of reference indicate corresponding parts in all the figures.

Figure 1 is a view partly in elevation and partly in section, showing my improved hanger supporting a wire; Fig. 2 is a vertical section on the line 2—2 of Fig. 1, looking in the direction of the arrow; and Fig. 3 is a perspective showing the hanger and clip.

A spanner hanger 4 is provided with eyes 5 and connected with the latter are span wires 6 whereby the hanger and parts connected with it are supported. Integral with the spanner hanger 4 and disposed centrally thereof is a round-top receptacle 7 and extending into the same are anchorages 8. The receptacle 7 contains a body of insulating material 9, preferably such as is commonly known in the trade as "Electrose." Embedded within this insulating material is a hanger bolt 10 provided with a head 11 and with an annular bead 12. The bolt 10 is further provided with a threaded portion

13 extending downwardly from the bead 12. A sleeve 14 is provided internally with a thread and is revolvably fitted upon the threaded portion 13 of the bolt. The 60 threaded sleeve 14 is provided with an annular flange 15 integral with it. At 16 is a nut having generally an annular form and provided with a contracted portion 17. A head 18 having generally a cylindrical form is provided with a cavity 19, also of substantially cylindrical form. This cavity is of greater diameter than the threaded portion 13 of the bolt and is of such depth that, when used as here indicated, its bottom is never quite reached by this threaded portion. At 20 is a clip and secured to the latter is a conductor 21 which may be a wire or cable. The head 18 is integral with the clip 20. The body portion of the nut 16 and the upper portion of the sleeve 14 are of angular form to facilitate the application of wrenches upon them, as will be understood from Fig. 2.

The head 18 of the clip 20 need not in every instance be made hollow. When my improved clip is to be employed with a hanger having a threaded bolt of standard length, say five-eighths of an inch, the head portion of the clip may be made solid without in any way affecting the operation of my invention. Should it be desired to apply my improved clip on a hanger having a bolt, say three-quarters of an inch in diameter, the only change required to be made is to employ a nut 14 having the internal diameter of its threaded portion tapped to three-quarters of an inch, or if desired, the original nut enlarged from five-eighths to three-quarters of an inch by running a three-quarter inch tap into it.

The operation of my device is as follows: In order to attach the clip to and detach it from the hanger, it is not necessary to remove the nut 16 from its mounting. This 100 can be done, however, if desired, by turning the sleeve 14 so as to remove it from the threaded portion 13 of the bolt. If the operator does not desire to remove the sleeve 14 from the bolt, he merely turns the nut 16. 105 The rotation of this nut feeds the head 18 gradually downward until the head is entirely released from the nut 16. During this movement of the nut 16 the contracted portion 17 of the latter turns with a swivel motion upon the flange 15. It may happen, 110 that the cylindrical cavity 19 in the head 18

is of an odd size, or it may happen that the head 18, having been once before used, has been worked over and on this account its cavity 19 varies in size from the one shown in Fig. 1. Again, it may happen that the head 18 has been used in connection with a clip of some other kind. If, for any of these reasons, it happens that the cavity 19 is of a larger diameter than that of the threaded portion 13 of the bolt, this does not prevent the head 18 from fitting perfectly, and consequently does not prevent the support of the conductor 21 by aid of my improved clip.

15 The usual way of removing the clip 20 from the hanger is to apply a wrench to the nut 16 and apply another wrench to the angular portion of the sleeve 14; then, by turning the first wrench, the head 18, normally 20 pressed tightly against the flange 15, is released from the latter, and this being done the rotation of the nut 16 is rendered very easy. This nut is turned until the head 18, carrying the clip 20, drops away from the 25 nut 16; or the removal of the clip 20 from the hanger may be effected in the following manner, namely: loosening the nut 16, then applying the wrench to the nut 14 and revolving the same until it is freed from the 30 bolt; the flange of the nut 14 acts as a swivel against the turned in portion of the nut 16. The operation of applying or removing my improved clip from a hanger or support is very simple and may be quickly 35 effected. My improved clips may be made short or long, as desired.

It will be noted that, owing to the shape of the spanner hanger 4, and more particularly to the position of the eyes 5, the clip 20 can not be turned completely around without striking these eyes. This is a matter of 40 no consequence in my hanger, for the reason that in order to mount the clip in position, or to disconnect it from the hanger, there is 45 no necessity to turn the clip relatively to the spanner hanger.

I do not limit myself to the precise form or construction of any or all of the parts herein shown and described, nor to the exact combination of parts as shown; neither do I limit myself in every instance to form the head portion of the clip hollow, as it will be apparent to those skilled in this art that changes may be made therein without

departing from the spirit or scope of my invention.

Having thus described my invention, I claim as new and desire to secure by Letters Patent:

1. A locking clip, comprising a spanner hanger, a bolt supported thereby and provided with an annular bead, and also provided with a threaded portion extending from said annular bead, a threaded sleeve revolvably mounted upon said threaded portion and provided with an annular bead, a nut having a contracted portion in engagement with said annular bead of said annular sleeve, said nut being threaded internally and revolvably relatively to said sleeve, a head threaded externally and fitting into said nut, and a clip connected with said head for supporting a wire.

2. A locking clip, comprising a hanger, a bolt supported thereby and provided with a bead, and further provided with a threaded portion extending from said bead, a sleeve threaded internally and revolvably fitted upon said threaded portion, said sleeve being adapted to jam against said bead and being provided also with an annular flange, a nut provided with a contracted portion for resting upon said annular flange, said nut being threaded internally, a head threaded externally and fitted into said nut, and a clip member connected with said head for supporting a conductor.

3. A locking clip, comprising a fixed bolt, means for supporting the same, a sleeve carried by said bolt and provided with a flange, said sleeve being further provided with an angular surface to be engaged by a wrench, a nut provided with a portion for engaging said annular flange, said nut being threaded internally, a head threaded externally and engaged externally by said nut, said head having a central compartment of greater diameter than said threaded portion of said bolt for receiving the latter, and a clip member mounted upon said head.

In testimony whereof I have signed my name to this specification in the presence of two subscribing witnesses.

LOUIS STEINBERGER.
